UNITED STATES PATENT OFFICE

JAMES ROBERT MEECE, OF PICKENS, SOUTH CAROLINA

GUANO DISTRIBUTOR

Application filed September 12, 1930. Serial No. 481,557.

This invention relates to guano distributors, the primary object of the invention being to provide an attachment to be installed on the usual distributor, to convert the distributor into a machine for sowing the guano over the ground surface.

An important object of the invention is to provide an attachment of this character having an operating shaft and a sprocket on the shaft to be engaged by the power chain of the distributor, eliminating the necessity of providing additional power means for operating the attachment.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a guano distributor equipped with a device constructed in accordance with the invention.

Figure 2 is a sectional view taken on line 2-2 of Figure 1.

Figure 3 is an enlarged fragmental view of the attachment.

Figure 4 is a plan view of the distributing blade of the attachment.

Figure 5 is a sectional detail view illustrating the connection between the body portion of the attachment and the swinging arm thereof.

Referring to the drawings in detail, the reference character 5 designates the supporting beam of the usual guano distributor, which is supported on the axle 6 on which the wheel 7 operates.

Mounted at the rear end of the beam 5 is the usual hopper 8 that feeds material through the spout 9 mounted at one side of the beam 5. Disposed within the hopper 8, is the usual agitator, not shown, the agitator being mounted on the shaft 10 that carries the sprocket 11 over which the chain 12 operates, the chain also passing over the sprocket 13

mounted on the axle 6, so that rotary movement of the wheel 7 will be directed to the shaft 10 and agitator mounted thereon.

The attachment comprises a base plate or body portion 14, which is formed with an upstanding longitudinal flange 15 having an opening to receive the bolt 16 that passes through the beam 5 to secure the base plate 14 to the beam. Secured to the plate 14 is a plate 17 that has downwardly extended portions 18 formed with openings to receive the shaft 19, there being provided a sprocket 20 on one end of the shaft 19, to be engaged by the chain 12, to direct rotary movement to the shaft 19. Secured to the shaft 19 at the opposite end thereof, is a wheel 21 that is provided with a cam groove 22 formed in the periphery thereof, the cam groove being designed to accommodate the pin 23 that extends downwardly from the arm 24 which supports the distributing plate 25. Thus it will be seen that due to this construction, the arm 24 will be shifted back and forth in a horizontal plane, to sow the guano over the ground surface.

The plate 25 is formed with a flange 26 disposed intermediate the side edges thereof, which flange acts to force the guano or material fed from the hopper, laterally over the ground surface.

As shown, the forward end of the arm 24 is provided with an upstanding pin 27 that operates in the tubular bearing 28 that is secured to the base plate 14, there being provided a head 29 on the pin 27 to prevent the pin from passing through the bearing 28.

From the foregoing it will be obvious that due to this construction, the plate 25 will be shifted laterally in a horizontal plane to evenly distribute the guano fed to the plate, through the spout 9, to the end that the guano will readily enter the soil to accomplish its purpose.

I claim:

In a fertilizer distributor, a hopper, a pivoted arm mounted on the hopper, a flat distributing plate mounted on the hopper, an upstanding flange extending longitudinally of the plate and disposed centrally thereof, a

spout leading from the hopper and adapted to direct material to the plate and flange, and means for swinging the plate laterally to throw material therefrom.

- 5 In testimony that I claim the foregoing as my own, I have hereto affixed my signature.

JAMES ROBERT MEECE.
